DESIGN FOR A WOVEN FABRIC.

SPECIFICATION forming part of Design No. 22,159, dated January 24, 1893.

Application filed December 30, 1892. Serial No. 456,847. Term of patent 3½ years.

To all whom it may concern:

Be it known that we, WILLIAM G. OLDHAM and WILLIAM K. SMITH, citizens of the United States, residing at Philadelphia, in the county of Philadelphia and State of Pennsylvania, have invented and produced a new and original Design for a Woven Fabric, of which the following is a specification, reference being had to accompanying drawing.

10 The leading feature of our design is the representation of a floral center piece, surrounded by a floral border, as illustrated by

the accompanying drawing; which is sufficient to enable others skilled as fancy weavers to produce our invention.

15 What we claim as new, and desire to secure by Letters Patent, is—

The design for a woven fabric, as shown in the accompanying drawing.
